United States Patent Office

Des. 199,855
Patented Dec. 22, 1964

199,855

PLANTER OR SIMILAR ARTICLE

Clinton C. Sullivan, 1413 Lindsay Drive,
Bakersfield, Calif.

Filed July 19, 1963, Ser. No. 75,875

Term of patent 14 years

(Cl. D35—3)

I claim:

The ornamental design for a planter or similar article, substantially as shown.
